TABULATING MACHINE

Fred M. Carroll, Yonkers, N. Y., and John H. Bakelaar, Paterson, N. J., assignors, by mesne assignments, to International Business Machines Corporation, New York, N. Y., a corporation of New York

Application July 18, 1929, Serial No. 379,190

18 Claims. (Cl. 235—92)

This invention relates to printing mechanisms for tabulating machines or the like, and is primarily directed to the provision of means for selectively feeding classified record sheets to a printing device for receiving data of the same classification.

It has heretofore been proposed to feed a card or bill to a printing device to receive a group of items and the totals thereof, such data constituting a statement of a particular person's account. Since it is desirable that such cards be classified in some manner it is essential that only those cards be fed to the printing device whose classifications compare with the classifications of the data entered. Otherwise, it is apparent that without the provision of such a device, entries may be effected upon the wrong records.

It is then a broad object of the present invention to provide for the selective feeding of a card or bill when the classification of the card or bill is identical with the classification of the items entered.

It is a further object of the invention to condition the machine when a discrepancy exists, in such a manner that the operator may be able to discern and rectify the error.

In connection with the above it is a further object to provide an indicating device for visibly indicating the classification of the items entered whereby the operator may observe the classification of the items entered and if necessary compare the same with the classification of the bill selectively fed to receive such items.

In the present instance the item entering means comprises record cards which are successively fed to the usual analyzing mechanism. The classification is represented by perforations and a similar means of classification is provided for classifying the bills. The cards and bills are preferably fed in an inverse relation and it is also an object of the invention to provide for the comparison of the records and bills when fed in this particular manner.

The present invention in its broadest aspects, may not contain the above feature and its adoption it should be understood, is to meet a particular situation, and with minor changes the comparing mechanism may be adapted to compare cards and bills fed in the same manner.

To these and other ends the invention consists in the novel features of construction, arrangement of parts, and combination of elements, hereinafter described, and more particularly set forth in the claims.

In the drawings:

Fig. 1 is a plan view illustrating one of the tabulating machine cards employed in the illustrative machine as the item controlling devices.

Fig. 2 is a representation of a bill or sheet adapted to receive the items and totals, the classification data appearing at the left end of the card.

Fig. 3 is a front view of a tabulator embodying the present improvements.

Fig. 4 is a view in side elevation taken on the line 4—4 of the machine shown in Fig. 3.

Fig. 5 is a front view of the comparing device shown in Fig. 7.

Fig. 6 is a view in side elevation taken on the line 6—6 of Fig. 3 and illustrates the bill feeding devices in detail.

Fig. 7 is a view in side elevation of parts of the comparing devices for the bills and record cards and is taken on the line 7—7 of Fig. 5.

Fig. 8 is a detail view taken on the line 8—8 of Fig. 5.

Fig. 9 is a view in side elevation of the device used to control machine operation upon a change in classification of groups.

Fig. 10 is a view in side elevation showing some of the parts illustrated in Fig. 7 but in different operated positions.

Fig. 11 is a plan view of the analyzing devices associated with the bills.

Fig. 12 is a plan view showing some of the operating connections for the platen.

Fig. 13 is a detail view of the platen detent mechanism.

Fig. 14 is a wiring diagram of the illustrative embodiment.

The improvements are shown in connection with the tabulator illustrated in the Lake Patent #1,600,413 dated September 21, 1926 to which reference may be had for details of construction of the card feeding, analyzing and total taking devices. Sufficient explanation of these devices will, however, be given to explain their coordination with the present improvements and other features of the illustrative machine.

Referring particularly to Fig. 14, the tabulator referred to includes a set of upper brushes 20 designated as the control brushes and a set of lower or adding brushes 21. The upper brushes analyze the perforations of the record card 22 (Fig. 2). The lower brushes 21 also analyze the perforations in the same field of the record card. The field 24 (Fig. 1) of perforations of the record card may comprise classification data in order that a disagreement of classification perforations of successive cards at the upper and lower brushes may cause the machine to go into an automatic

60

105

110

total taking operation more fully explained in the Lake patent. In the event of continued agreement of successive cards the machine will continue with the item entering operations controlling printing and adding instrumentalities in accordance with the data representing perforations of other fields.

In the present embodiment the machine is adapted to print the items 25 (Fig. 2) and the totals 26 thereof upon a card designated herein-after as a "bill" 27. The bill 27 also contains classification perforations 28 and a printed number 29 which is a translation of the classification perforations and is provided for the convenience of the operator in discerning discrepancies. A new bill is fed as an incident to each total taking operation at which time the first card of a new group is already at the control brushes 20. Upon the agreement of the classification perforations 24 and 28 the machine will proceed with item entering operations of the new group but any discrepancy between the new bill fed and the first card of a new group will be observed by the operator by stoppage of the machine.

It should also be observed that in the present embodiment the record cards 22 are fed by the card feeding mechanism with the "9" index points leading while in order to get a proper print on the face of the bill, the latter is fed with the "0" perforations leading. The present improvement also provides for the checking of cards and bills when fed to their analyzing brushes in an inverse relation.

The circuit arrangement in connection with the control brushes 20 comprise cam controlled contacts 29a intermediate the line side 30 and brushes 20, the latter being plugged by wires 31 to control magnets 32 which are permanently connected to the other line side 33 by a wire 34. The plug connections are only shown for one order, it being obvious that as many units are plugged as there are columns analyzed. Upon the passage of the first record card of a new group past the control brushes 20 and which is concomitant with the item entering operation of the last card of the last group, impulses will be transmitted to magnets 32 at differential times.

Each magnet when energized attracts its related armature 35 (Fig. 7) to unlatch a stop member 36 which is then urged by a spring 37 to bring a stop portion 38 in engagement with one of a series of notches 39 formed in the periphery of a spider 40. Three spiders 40 are provided for each column and they are driven frictionally by a shaft 41 which is given a third of a revolution for each card cycle. The notches 39 pass by the stop portions in synchronism with the index points of the record card 22 fed past the control brushes 20.

When a spider 40 is stopped by an extension 38 the spider will be held back during a portion of the cycle of operation of shaft 41 and then released to permit a supplemental movement. Prior to the end of the cycle the stop member 36 will be relatched to permit the spider to be driven supplementally, this movement occurring during the time the blank portion of the record cards above the "0" index points is being fed past the brushes 20. During the next cycle of operation, which it will be recalled, is a total taking cycle if cards disagree, the spider will be driven by connections from the total taking devices. The holding back of the spider caused by the actuation of stop member 36 is equivalent in units to the numerical value of the index point perforation of

the record card in the particular column analyzed. For example if the units index point was "3" the spider would be held back 3 steps of operation.

For the present it may be considered that each spider 40 is provided with a cam portion 42 adapted to engage a foot 43 of a contact operating lever 44 loosely pivoted upon a rod 45 so that the engagement of the elements 42 and 43 will cause the arm 44 to be rocked to close contacts 46. Since the spider 40 has been held back a number of steps which is equal to the numerical value of the index point of the tabulating card analyzed the actuation of contacts 46 will be accordingly held up a complementary amount during the total cycle.

Since the particular means utilized to cause the machine to enter into a total taking operation as an incident to change in card groups is different from that shown in the Lake Patent #1,600,413 an explanation of this unit will now be given, but for the more detailed description of this unit, reference may be had to the Carroll Patent No. 1,726,539 dated September 3, 1929.

Impulses caused by the passage of an upper brush 20 through the card perforation causes energization of a related magnet 47 the latter being plugged to the related brush by a plug connection 48, the group of magnets 47 having a connection to the line side 33 by wire 34. By jumper or plug connections 49 the other magnet 50 of a pair 47-50, see Fig. 9, is serially connected to the related one of the lower brushes 21, one side of the group of magnets 50 having a return connection to the line side 30 by a wire 51.

Referring particularly to Fig. 9 each pair of magnets 47-50 is associated with a balanced armature 52 having a wedge-shaped terminal 53 fitting in a similar shaped notch of one arm of a bell crank 54. The armature is held in a neutral position by a spring 55 and is active to keep contacts 56 closed against the normal tension of the upper blade which tends to maintain the contacts 56 open. The pairs of contacts 56 are series connected (Fig. 14) in a circuit 57 and the connections therefrom to the rest of the electrical apparatus is similar to the Lake Patent No. 1,600,413 hereinbefore mentioned. It is sufficient to state that when impulses are transmitted to a pair of magnets 47-50 simultaneously the armature 52 will remain in a neutral position and if this action is the same for all controlling columns, the series of contacts 56 will remain closed and the machine will continue with item entering operations. A dis-simultaneous energization of a pair of magnets 47-50 will, in the manner fully explained in the Carroll Patent No. 1,726,539, cause the related pair of contacts 56 to be opened and since the circuit 57 is now opened a total taking operation will ensue, as fully explained in the patent No. 1,600,413. At the end of the total taking cycle the contacts 56 are closed in relatched position by a bail member 58 pivoted at 58a and operated by a cam 59. In operation the bail member 58 depresses the upper blade of contacts 56 to close said contacts and far enough so that the upper blade is below the lower end of the vertical arm of the related bell crank 54, whereupon spring 55 is now effective to shift said arm over the upper blade to keep contacts 56 closed as bail member 58 is shifted upwardly to its normal position.

As an incident to each total taking operation a shaft 60 (Fig. 4) is rotated and through suitable connections a new bill is fed to the bill analyzing brushes. Prior to the explanation of the devices

150

for effecting the above function the means for driving the spiders 40 during the item entering operations will first be described.

In the Hollerith tabulator a shaft 61 (Fig. 4) is rotated during each item entering operation. By a pair of bevel gears 62 a connecting shaft 63 is similarly driven. The upper end of the shaft 63 carries a bevel gear 64 in mesh with a bevel gear 65 (see Fig. 12 also) secured to a stub shaft 66. The latter is adapted to drive a shaft 67 by a pair of one-to-one ratio gears 68. Shaft 67 (see Fig. 6) has secured thereto a notched element 69 the notch of which is adapted to be received by the engaging end of a spring urged pawl 70 pivoted to a profile cam 71 (see also Fig. 5). By a connecting sleeve 72 cam 71 is secured to a pinion 73 which is in mesh with a gear 74 secured to the shaft 41. When shaft 67 is driven the notch in disk 69 engaging pawl 70 drives cam 71 and the connected gear 73, the gear ratio being so selected as to provide an angular movement of gear 74 and shaft 41 of 120° for each card cycle. The shaft 41 is adapted to receive the series of spiders 40 which are arranged and mounted on the shaft 41 and urged together by a spring 75 so that they may be frictionally driven by the shaft collectively but each stopped independently at differential times, as before explained.

It is also desirable to be able to know the group number of each card passing the control brushes and to this end each spider has secured to it an irregular shaped cam plate 76 (Fig. 7) in the plane of a feeler finger 77 and which cam plate has the aforementioned cam portion 42. For each order an indicator segment 78 is provided bearing indicia one of which is visible through a sight slot 79a (Fig. 3) to visibly indicate the position of the related indicator segment 78. Each indicator segment is loosely mounted on shaft 45 (Fig. 7) and has a link connection 79 to an integral arm 77a of the feeling finger 77. A series of the latter are pivoted on a shaft 81 dependingly hung from shaft 45 by a pair of arms 80 (see Fig. 5).

The arms 80 as shown in Fig. 5 are secured to the shaft 45 and the latter has secured thereto an arm 83 carrying a roller (see Fig. 8) engaging a profile cam 84 driven by shaft 67 in a clockwise direction. As the shaft revolves the cam 84 will rock shaft 45 and by rocking frame 80—81 downwardly from the Fig. 7 position to the Fig. 10 position it will cause the feeler fingers 77 to be shifted so that one of the feeler fingers 77 is caused to engage a cam edge 85 of the particular element 76 in cooperation therewith and which at this time is stationary in its position of adjustment. As each feeler finger strikes its related cam during a continued downward movement of frame 80—81 caused by rotation of cam 84 it will be rocked about its pivotal point 81 thus elevating the related indicator segment 78 through the medium of link 79. The rocking of a feeler finger continues until frame 80, 81 is in its extreme shifted position determined by the cam 84, as shown in Fig. 10. This position of adjustment will be held by a pawl 82 pivoted on a fixed rod 82a engaging the appropriate one of a series of notches 86. It is understood of course, that the final positioning of the indicator is dependent upon the position at which the cam element 76 is stopped at the end of the analyzing cycle and, in turn, represents the index point analyzed.

In more detail, if cam 76 occupies the full line

position shown in Fig. 10 as shaft 81 is shifted to the right from the Fig. 7 position, finger 77 will approach the cam edge 85 of cam 76 and engage the cam before the movement of shaft 81 is stopped. Upon further movement of shaft 81, while finger 77 contacts with cam 76, the finger 77 and its arm 77a will be rocked clockwise about shaft 81 to the position shown in Fig. 10, thereby straightening the toggle formed by arm 77a and link 79 thus rocking the indicator segment to the position shown in Fig. 10 so that the numeral "7" is at the reading line.

After the parts have been positioned as shown in Fig. 10 continued rotation of cam 84 in a clockwise direction will permit the frame 80, 81 to be restored to the position shown in Fig. 7, the feeler fingers 77 being withdrawn from cooperation with the cam elements 76. Since arms 80 will be merely rocked about their pivotal connections to the indicating segments no movement will be imparted to the latter. The indicator segments will remain in their positions of adjustment latched by pawls 82. The latter are rocked by a bail 87 at the beginning of the next card cycle, the bail being operated by a cam 88 (Fig. 100) secured to drive shaft 67 and when the pawls 82 are rocked sufficiently to withdraw them from engagement with the notches 86 the indicator elements will drop to their lowermost positions, as shown in Fig. 7. The pawls however, subsequently reengage said notches to hold the indicator segments in their newly adjusted positions. The pawls hold the indicators after a card has been read and since shaft 67 is driven clockwise only during item entering operations to operate the pawls 82 to release the indicators the indicator reading is held during the total taking operation.

Since there are three spiders 40 for each column as shown in Fig. 7 in connection with a single column a corresponding number of stop pawls 36 are provided, each pawl 36 being in the plane of the related spider. Since only a single pawl is effective during one cycle it is desirable to lock the other pawls of the set and to this end a hollow tube 89 (Figs. 5, 7 and 10) is provided and for each set of pawls 36 a plurality of slots 90 are provided. When a certain pawl 36 is to be effective its related slot 90 is positioned with respect to the tail 91 of the pawl to allow it to enter (see Fig. 125) when the armature 35 is attracted. At other times the tail 91 of the pawl will ride on the periphery of the tube 89 and is thereby locked against movement. Tube 89 has secured thereto at its end a gear 92 (Figs. 5 and 6) in mesh with a gear 93 attached to the gear 74 so that rotation of the tube 89 may be effected as an incident to each card cycle and total cycle as well.

Restoration of the operated pawls 36 is effected by a bail 94 which extends transversely to cooperate with the complete set of pawls 36 (Fig. 5) said bail being operated by a cam 95 (Fig. 8) secured to drive shaft 67 and cooperating with an extension 96 of one arm of the bail member 94.

It is, of course, necessary to restore the stopped spider 40 to its proper position in order that it may properly control the contacts 46 in a subsequent operation. Extending transversely of the spiders 40 is a bail 97 (Figs. 5 and 7) in which is journaled a rod 98 carrying pawl members 99, 145 each member 99 having a set of three teeth 100, (see Fig. 5) each of which is in the plane of a shoulder 101 of the cam plate 76 attached to the related spider 40. Each arm of the bail 97 is provided with teeth 102 in mesh with the teeth 150

of segment racks 103 secured to a rock shaft 104. One end of shaft 104 has secured to it a depending arm 105 (Figs. 5 and 6) carrying a roller in engagement with the cam 71 hereinbefore referred to.

A downward movement of the bail 97 will cause the teeth 100 to engage the stop shoulders 101 of the stopped spiders 40 to positively restore them to their normal starting positions. This 10 operation of course, occurs several cycles of operation subsequent to the time a spider 40 is stopped by its related pawl 36.

As premised hereinbefore, upon a change in card group the machine is conditioned for a total 15 taking operation, during which operation a new bill 27 is fed and it is determined whether it corresponds with the first card of the new group. For accomplishing this function the shaft 60, which is driven as an incident to a total taking 20 operation in the tabulator disclosed in the Lake Patent No. 1,600,413 drives a connecting shaft 106 (Fig. 4) by a pair of bevel gears 107. The upper end of shaft 106 carries a bevel gear in mesh with a bevel gear 108 secured to the drive shaft 109.

25 Shaft 109 has secured thereto a gear 110 (Fig. 6) adapted to drive a gear 111 through an intermediate pinion 112. The pairs of feeding rollers 113 and 114 are intergeared and the lower gear of each set meshes with the larger gear 111 so that 30 a driving connection is established between shaft 109 and the feeding rollers 113 and 114.

Feeding of the bills singly from the supply hopper 115 is effected by a picker 116 of the usual form and is reciprocated by a pair of arms 117 35 secured to a rock shaft 118, the latter having secured thereto an arm 119 carrying a roller engaging the race of a box cam 120 secured to shaft 109. Each revolution of the cam 120 will cause the picker 116 to feed the lowermost bill 40 to the feeding rollers 114 in order that the bill perforation analyzing brushes 121 may analyze the classification perforations of the bill, (see also Fig. 11). The bill is fed from the brushes 121 to a rotatable platen which is driven concomitantly 45 with the feeding rollers so that the bill is fed around the platen 122 between the periphery thereof and a set of spring urged rollers 123.

Reverting now to the wiring diagram (Fig. 14) it will be observed that brushes 121 are serially 50 connected through cam controlled contacts 124 (see also Fig. 6) to the line side 33 and each brush 121 is serially connected through its related magnet 125 and a pair of contacts 46, hereinbefore mentioned, the latter being connected to the 55 other line side 30 by a wire 126.

By reason of the above connection it will be apparent that if a contact 46 is closed by a spider 40 synchronously with the closure of the circuit at the brush control 121 the related magnet 125 60 will be energized. It is therefore necessary to close contacts 46 at a point during the succeeding or total taking cycle to determine whether the index point of a column of the first card of a new group coincides with the perforation in a 65 corresponding column of the bill. Due to the inverse relation of feeding the record cards and the bills the contacts 46 are closed at a point in the cycle which is the nines complement of the points in the cycle of the energization of magnet 70 32, thus making possible a comparison of the bills and record cards.

Means are therefore provided for driving the spiders 40 to obtain a closure of contacts 46 during the total taking cycle and referring to Fig. 75 it will be seen that secured to shaft 109 is a

cam 127 engaging a roller 128a of a bell crank lever 128 connected to segment 129 by a link 130 to effect a reciprocation of the segment by the cam 127. The segment teeth drive a pinion 131 loose on shaft 41 and secured to the pinion is a disk 132 carrying a pawl 133 in engagement with a notched disk 134 secured to shaft 41. The throw of the segment 129 is such that engagement of the pawl 133 with one of the notches in disk 134 is adapted to effect an angular movement of 240° of shaft 41. It should also be observed that the functions effected by shaft 67, such as release of pawls 82, reciprocation of feeding fingers 77, and operation of bail 94 are not effected during a total taking operation. However, cam 71 is operated during total taking operations to restore the stopped spiders for readiness during the next item entering operation.

If, as before stated, a magnet 125 is energized by reason of a similarity in the card and bill perforations, the armature 135 (Fig. 6) thereof will be attracted to effect closure of contacts 136, each set of contacts being individually latched by pawls 137. As is best shown in Fig. 6 a vertical arm 135a of each armature 135 has provided at 10 its upper end a notch 135b which is normally engaged by the end of the related pawl 137, the resiliency of the right hand contact blade of contacts 136 maintaining this relationship. When a magnet 125 is energized the vertical arm 135a will 10 be shifted to the left as viewed in Fig. 6 to close contacts 136, thereupon the related pawl 137 will be urged by its spring 136a to engage the portion of the arm 135a which is above the notch 135b to thereby hold contacts 136 in closed position. 11 Contacts 136 are series connected and if at the termination of the operation of comparing a bill with a record card, all the contacts 136 are latched closed, a circuit 138 (Fig. 14) will be closed. This circuit is in the automatic starting circuit fully 11 explained in the Lake Patent No. 1,600,413 and when closed permits the machine to go into a tabulating operation in connection with the new group of cards. In the event that the perforations in a particular card column do not coincide the 12 circuit 138 will be opened and the machine will stop, allowing the operator to visibly compare the bill with the record card to correct the discrepancy. This comparison is readily effected since the operator may read the classification number 12 29 of the bill (Fig. 2) and compare it with the classification number of the record card as exhibited by the indicators 78 and which is retained during a total taking operation.

Contacts 136 are unlatched during the first 13 tabulating cycle by a bail 139 secured to a shaft 140 (Figs. 4 and 6) to which is secured a lever 141 actuated by a pin 142 (see Fig. 12).

The machine also includes several groups of printing bars 143 (Figs. 3, 4 and 6) adapted to be 13 struck by hammers 144 to effect printing of items 25 (Fig. 2) or the totals 26 thereof upon the bill 27 in the manner fully explained in the Lake Patent No. 1,600,413.

Certain other adjuncts related to the printing 14 devices are also employed among which is a feeding device adapted to give a head spacing to the bill to accommodate the usual printed heading and to determine where the first item may be printed. In the present embodiment this comprises a cam 145 (Fig. 4) secured to the total shaft 109 and which rocks a bell crank lever connection 146, one arm of which is connected to a link 147, the latter being adjustably mounted on the arm by a device, such as that illustrated by numeral 154

148. The link 147 is articulated to a drive segment 149 in mesh with a gear 150b adapted to drive the platen 122 by a train of gears 150, 151 through a pawl and ratchet device 151a (Fig. 12). This driving connection is effective to rotate the platen a predetermined amount to effect the desired initial spacing of the bill.

For the purpose of effectively stopping the rapid rotation of the platen when the desired amount of bill feed has been accomplished, the detent device such as that illustrated in Figs. 12 and 13 is preferably employed. In cooperation with a ratchet wheel 152 rotatable with the platen is a detent or pawl 153 impositively held by a spring 154 to engage the interdental spaces of the ratchet wheel. The detent mechanism is normally in the position shown in Fig. 13 and impositively holds the platen during printing time but the pawl is held out of engagement with the ratchet wheel 20 during the time the bill is ejected by mechanism to be described hereinafter and also during the time the platen is rotated for head-spacing the bill. To this end there is secured to shaft 109 a cam 155 having a low portion 156 and high portions 157.

25 During sheet ejecting and platen rotating time the high portions 157 act upon a rod 158 through bell crank lever 161 and force the pawl 153 downwardly against spring 154 and by means of a camming slot 159 and guide pin 160 the pawl 153 is shifted away from the ratchet wheel 152. At the termination of the above operation the low portion 156 of cam 155 permits the spring 154 to urge the pawl to reengage with the ratchet wheel to prevent overthrow of the platen roller and impositively position the platen. The detent mechanism, however, is effective at a line spacing operation permitting one or more steps of rotation of the roller and held in such position by the interdental spaces of the ratchet wheel. The line-spacing devices for spacing the imprints form no part of the invention and any suitable form may be employed. As herein provided for, the Lake machine comprises a rock shaft 162 (Fig. 4) to which is secured an arm 163 connected by a link 40 164 to a lever 165. A lever 166 secured to the pivotal supporting shaft of lever 165 has a link connection 167 to a pawl-carrying disk 168 which through a pawl and ratchet device 169 (Fig. 12) turns gear 150 to rotate the platen to space the 45 items and totals.

50 Additional mechanism is also provided to eject a printed bill as an incident to each total taking operation and as shown includes a set of rollers 170 (Figs. 4 and 6) and a supplemental set of rollers 171 mounted on a rockable frame 172. The rollers are intergeared by gears 173 to eject a bill between rollers 170 and 171 when the frame 172 is rocked to cause the rollers to grip the bill therebetween. The frame 172 has pivoted thereto a link 174 connected to a lever 175 which is rocked by a box cam 176 (Fig. 6) secured to the shaft 109 and is effective to couple the rollers 170 and 171 together to frictionally feed a bill from the platen after which the bill is guided by a plate 177 (Fig. 4) to fall in a receptacle 178.

55 The gear 173 rotatable with rollers 170 is driven by a train of gears 174', 175', the latter meshing with the gear secured to the upper feeding roller 113.

60 In the event that the bill does not properly check with the first record card of a new group the proper one can be inserted in the hopper and the machine run through a regular reset or total cycle. This will cause the improper bill to be ejected and the proper bill fed to the platen. To carry out 65

the above the regular reset key 180 (Fig. 14) is depressed causing the machine to function in the manner described in the Lake Patent No. 1,600,413.

70 If the bill is in the proper sequence and the record card or cards of a group be in error, the latter may be run out of the machine by the provision of the usual listing or starting key fully shown and described in the Lake Patent No. 1,600,413. Since it is desirable not to have the items or total of such a group printed on the bill, certain other expedients are also employed. To this end there is provided a clutch device 181 (Fig. 4) which disables the connection between bevel gears 107 to prevent the feeding of a bill to the platen at the end of the improper record card or groups of cards. The printing of items or totals on the bill encircling the platen is prevented by shifting of a rod 183 by a lever 184 which shifts the hammers 144 towards the type to render them ineffective with respect to the operating bail 185. The function and operation of the latter is explained in the Lake Patent No. 1,379,268 to which reference may be had for further details of construction and operation.

75 While there has been shown and described and pointed out the fundamental novel features of the invention as applied to a single modification it will be understood that various omissions and substitutions and changes in the form and details of the device illustrated and in its operation may be made by those skilled in the art without departing from the spirit of the invention. It is the intention, therefore, to be limited only as indicated by the scope of the following claims.

80 What is claimed is as follows:—

1. In a machine of the class described the combination with a device adjustable to one of a series of different positions, of means for causing the adjustment of said device, record controlled means for effecting a position of the device as it is adjusted by the last named means dependent upon the index point analyzed, and means under control of said device when adjusted by the adjusting means for converting the index point reading to a 85 complementary reading.

2. In a machine of the class described the combination with movable devices, of record controlled means for setting said devices individually to different positions dependent upon the numerical values of the index points analyzed, and means whereby movement of said devices collectively causes said devices to read out the complement of the numerical values.

3. In a machine of the class described the combination with a set of devices movable synchronously with the passage of a tabulating card past an analyzing element, of means for stopping said devices individually at different positions, and means for moving said devices collectively to read out the complement of the index points of the 90 card.

4. In a machine of the class described the combination with a device movable synchronously with the passage of a tabulating card past an analyzing element, of means for moving said device, means under control of the element for causing said device to be stopped in its movement effected by the moving means at a position dependent upon the index point analyzed, and means whereby said device during its movement 95 by the moving means converts the index point reading to a complementary reading.

5. In a machine of the class described, analyzing mechanism for analyzing designations on a pair of records inversely with respect to each other as 100

- indicated by their relative index points, and means controlled by said analyzing mechanism for comparing the designations to signify the agreement or disagreement in designations of the 5 pair of records analyzed. 80
6. In a machine of the class described, means for analyzing and comparing designations of a pair of records inversely with respect to each other as indicated by their relative index points, 10 and means controlled by said analyzing means for comparing the designations for controlling machine operation in accordance with the agreement or disagreement of the designations of the pair of records analyzed. 15
7. In a machine of the class described, means for analyzing a designation of a record, means for setting up an element to represent a complement of such designations, and means for analyzing a designation of another record whose index 20 points are analyzed in an inverse relation with respect to the index points of the first named record concurrently with the reading out of the setting of the element. 90
8. In a record controlled machine, means for 25 analyzing classification designations and item representing designations of tabulating cards fed in successive groups, means for analyzing classification designations of a record constituting a bill, means for representing upon the bill items represented by a group of tabulating cards, means 30 under control of the classification designation analyzing means of the card and bill for comparing the classification designations of one of the tabulating cards of one of the groups with the bill 35 to control the representing of the items on the bill if they agree, and means for printing a total of the items upon the bill when the classification of tabulating cards changes. 105
9. In a record controlled machine, means for 40 analyzing item representing designations of tabulating cards fed in successive groups, means for analyzing and comparing classification designations of one of the cards of a group with the classification designations of one of a group of 45 individual records constituting a bill, means for automatically feeding a bill for each group of tabulating cards, means for printing the items upon the bill dependent upon the determination of the analyzing and comparing means, and means including accumulating means for printing 50 a total upon the bill receiving the items when classification designations of tabulating cards change and for causing automatic operation of the feeding means. 110
10. In a record controlled machine, a series of 55 records having classification designations, means controlled by a series of tabulating cards having classification designations for printing a series of items and a total upon one of said records, means for analyzing and comparing the classification designations of one of the tabulating cards and one of said records, and means whereby the last named means causes the printing of items and a total when the records analyzed bears the 60 same classification designations as one of the controlling tabulating cards. 115
11. In a machine of the class described, means under control of a series of tabulating cards having classification designations for printing items indicated on said cards upon one of a series of 65 records having classification designations, means for analyzing the classification designations of successive tabulating cards to effect the continuity of item printing operations while the designations agree, means controlled by said analyzing 70 means for controlling the printing of a total upon the record printed with said items when designations of successive cards disagree, means for presenting another of said records, and means for analyzing the classification designations of the record presented to compare them with the designations analyzed by the tabulating card analyzing means. 80
12. In a record controlled machine, means for entering a series of classified items and a related total upon a record, means for comparing the classification of the items with the classification of the record represented by designations on the record to determine the printing of items, and means whereby the total is printed upon the record when successive item entering means are unlike in classification. 85
13. In a record controlled machine, means for entering a series of classified items upon a record classified by designations thereon, means for printing a related total upon the record when successive entering means are unlike, means for analyzing the classification designation of the record and upon agreement with the classification of items cause item entering upon the record, and means dependent upon unlike classification of successive items for presenting another record for receiving items all of the same classification but different from the items entered upon the 90 record. 95
14. In a machine of the class described, the combination with means for entering items of the same classification upon one of a series of records having classification designations, of means for analyzing the designations of one of the 100 records for comparing the classification represented thereby with the classification of the items to be entered and to cause item printing if classification agrees, and means to cause the printing of a total upon the record receiving the items 105 and automatically cause during the total printing cycle the feeding of a succeeding record to the analyzing means to compare the classification designations of the succeeding record with the classification of items to be subsequently entered. 110
15. In a machine of the class described, the combination with a series of classified records, of means for printing items of the same class and a related total upon one of the records similarly classified, means for analyzing classification designations of one of the records to determine the printing of items and a total thereon, and means effective upon printing a total upon one of the records for positioning a successive record for 115 subsequent printing operations thereon. 120
16. In a machine of the class described, the combination with classified records constituting bills, of means for analyzing classification designations on one of said bills, means for printing a total of a series of items of the same class upon 125 one of said bills, and means whereby said analyzing means controls the printing of the total by comparison of the classification designations with the class of the series of items making up such total. 130
17. In a machine of the class described, means for analyzing a designation of a record while in motion and subsequently reading out such designation, means for analyzing a designation on another record while in motion after the first named record has been analyzed but concurrently with the reading out of the designation of the first named record, and means controlled by the last named means effective during the reading 140 145
- 150

of the second record for determining agreement or disagreement of the designations compared.

18. In a machine of the class described, means for analyzing and comparing classification designations of a bill with those of one of a series of tabulating cards, said designations being analyzed inversely with respect to their relative

index points and means dependent upon the analyzing and comparing means for printing upon the bill a series of items represented by the series of tabulating cards and a related total.
